UNITED STATES PATENT OFFICE.

CECIL WEBB, OF LISBURN, IRELAND.

TWO-STROKE-CYCLE INTERNAL-COMBUSTION ENGINE.

Application filed January 27, 1920. Serial No. 354,476.

To all whom it may concern:

Be it known that I, CECIL WEBB, a subject of the King of Great Britain and Ireland, residing at Lisburn, county Antrim, 5 Ireland, have invented certain new and useful Improvements in Two-Stroke-Cycle Internal-Combustion Engines, of which the following is a specification.

This invention relates to internal combustion engines of the two-stroke-cycle type, in which three or multiples of three compound cylinders are fitted each with a differential piston acting on a common crank shaft with a distribution of 120° around the crank circle, and in which the larger diameter of each cylinder and piston acts as a pump to deliver a gaseous combustible mixture to the smaller diameter of an adjacent cylinder, in which it is compressed, ignited and expanded.

10 It does not apply to engines which use a system of air scavenging.

The object of the invention is to provide improvements in engines of the kind referred to, with a view to obtaining effective "lead" 25 as between "pumping and exhausting," and as between "compressing and pumping," so as to combine the advantageous scavenging and high volumetric efficiency, which may be obtained by means of differential pistons, 30 with the excellent torque of a two-stroke-cycle engine having three cylinder distribution of crank effort; and to do this in such a manner as to achieve a large power output by maintenance of a high rate of revolution.

35 The highest degree of volumetric efficiency and advantageous scavenging in engines of this type, using a gaseous mixture, is obtained when the displacement volume of the pump portion is equal to the total volume 40 of the firing portion of the compound cylinder, and when the whole of the gas in the pump can be transferred to the firing chamber without loss. A high rate of revolution with large power output, can be obtained 45 only when the area of the exhaust ports is sufficient to allow of very rapid exhausting.

To obtain these results I arrange an effective system of "leads" as above stated. By 50 the expression "lead as between pumping and exhaust" I mean not only that the pump shall have moved through a large portion of its delivery stroke, and therefore that the pressure of the gas inside the pump has 55 been raised considerably before the exhaust ports are opened, but that this high pressure

shall not have been impaired because of leakage.

By the expression "lead as between compressing and pumping" I mean that the exhaust ports shall have closed, and compression shall have commenced, before the pump has completed its delivery stroke.

The object of my invention is secured in a manner now to be described with reference 65 to the annexed drawings whereon I have shown, for the purpose of illustration, preferred embodiments of the invention.

Fig. 1 is a cross section through one of the cylinders of an engine embodying my im- 70 provements.

Fig. 2 is a longitudinal section through the engine to a smaller scale.

Figs. 3, 4 and 5 are diagrammatic views 75 hereinafter specifically referred to.

On the drawings the same reference letters and numerals wherever occurring indicate the same or similar parts.

To cause each pump to move through a large portion of its delivery stroke before 80 the exhaust ports in the cylinder to which the pump delivers are opened I make the ratio of the longitudinal dimension of the exhaust ports very small with regard to the piston stroke. This is made practically pos- 85 sible by the insertion in each cylinder of a liner L. The function and advantages of this liner will be more fully described when dealing with the question of "lead as between compressing and pumping." When a 90 pressure considerably above atmospheric is obtained in the pump cylinder leakage may occur between the piston and cylinder walls when the piston rings have moved above the level of the exhaust ports and I prevent this 95 by inserting in each cylinder a ring or rings shown at C. The rings contract upon the sides of the pistons which move in relation to them.

If the displacement volume of each pump 100 equals the total volume of the firing cylinder to which it delivers and the pump has completed its delivery stroke before the exhaust ports in the firing cylinder are closed, a portion of the gas delivered will escape through 105 the exhaust ports, and the volumetric efficiency of the engine will be greatly reduced. This condition is inevitable when the piston is used as a valve to open and close the inlet or transfer ports, as well as the exhaust 110 ports, because the latter must open first and close last. I therefore direct the gas from

the pump through a check or transfer valve to the head of the firing cylinder.

Furthermore, if the area of the pump annulus were equal to the area of cross section 5 of the firing cylinder, it would be necessary that the exhaust ports should close when the pump and firing portions of pistons were in the positions shown at Fig. 5 in which P represents position of pump and C the position 10 in firing cylinder.

But since the area of the annulus is greater than the area of the cross section of the firing cylinder in the same ratio as the total volume of firing cylinder is to displacement 15 volume of the piston of the same cylinder, therefore the exhaust ports may close slightly later, in order to exhaust an additional volume of the spent gases, equivalent to the clearance space of the explosion cylinder, 20 and still avoid waste of fresh gases, so that I close the exhaust ports as shown at Fig. 4, P being pump and C being firing portion of pistons.

In Fig. 4 the exhaust ports shown 1-2 25 have a ratio of .12 to the length of stroke shown 1-3. This is a very considerable restriction of port dimension measured longitudinally of the cylinder, and this necessitates great increase of circumferential dimension, unless the port area be very small 30 with consequent low power output.

When however the circumferential dimensions are greatly increased the strength of the cylinder to resist longitudinal stress 35 is greatly reduced, and in any case there are serious constructional difficulties when the exhaust ports are formed in the cylinder castings.

Each liner L has exhaust ports E cut in 40 it. As the liner is not subject to longitudinal stress, the ports E may be cut throughout a very large portion of its circumference, leaving only such solid metal as is required to prevent piston rings from becoming displaced.

The provision of this ample port area, with but a small longitudinal dimension, enables me to secure the "leads" desired, namely:—The pump has obtained a considerable compression before the exhaust ports are opened, consequently a rapid transfer of gas takes place, and the exhaust ports have closed considerably before the pump has completed its delivery, thus 55 avoiding waste through the exhaust and securing the highest volumetric efficiency.

Other advantages also accrue from the use of this liner, namely:—Simplification of construction in the matter of coring and 60 casting, and ease of renewal after cylinder wear; also if the engine is water cooled the water jacket can be carried down around the exhaust chamber, cooling and reducing the pressure of exhaust gases, and assisting rapid discharge; also if it is desired to 65

construct a very light engine, the liner, which alone is subject to wear may be made of a hard material such as iron, whilst the body of the engine can be made of a light metal such as aluminium or of a light alloy. 70

R (Fig. 1) is a rotary distributor conveying gaseous mixture from a carburettor or other fuel supply to the pump P', T is a transfer passage through which the pump delivers the gaseous mixture to the firing 75 space F₂ (Fig. 2) of the next adjacent cylinder and W is a water jacket. The rotary distributor R consists essentially of an outer case 1 attached to the pump cylinder, and a rotating tube 2 which has apertures cut in it so as to allow gas to pass through ports into the pump cylinders in proper sequence. A carburettor or other gas supply is attached to one end and it is actuated by a suitable gear at the other end. 80 The gear is driven from the engine crank-shaft.

In engines of the type which has been defined it has been the common practice to admit gas to the pump cylinder 90 through a valve which is held open during the suction stroke by the pressure of the flowing gas. By the improvement here defined there is no restriction to the flow of gas, and it will continue to flow into the 95 pump cylinder until the momentum of the gas has been expended in very fully charging the pump, hence it materially contributes to volumetric efficiency.

Gaseous mixture is transferred from the 100 pump P₁ to the firing cylinder F₂ through a check valve V₂.

In like manner gaseous mixture is transferred by way of transfer ports similar to T (Fig. 1) from P₂ to F₃ through valve 105 V₃; and from P₃ to F₁ through valve V₁.

Fig. 3 shows the compression lead in the pump when the exhaust ports are open, P being position of pump piston and E the position of piston head in a firing cylinder 110 at moment when exhaust ports are being opened. The compression in the pump is thus about 28 lbs. per square inch at this moment, and, as the pump piston is at this time travelling very fast, a high pressure 115 is maintained making rapid transfer effective.

P in Fig. 4 is the position of the pump piston when the exhaust ports in the cylinder to which it delivers are closing; and the ratio of exhaust port to piston stroke is shown as the ratio of the distances 1-2 to 1-3, that is about .12.

Having now fully described my invention what I claim and desire to secure by 125 Letters Patent is:—

1. In an internal combustion engine, of the type referred to, the combination of three cylinders having explosion and pumping chambers, a crank shaft having cranks 130

- distributed at 120° around the crank circle, liners in said explosion chambers having exhaust ports therein, differential pistons in said cylinders, packing rings in said 5 liners to prevent leakage from pumping to explosion chambers, means for admitting gas to the pumping chambers of the cylinders and means for admitting gas from the pumping chamber of one cylinder to the 10 explosion chamber of another cylinder.
2. In an internal combustion engine, of the type referred to, the combination of three cylinders having explosion and pumping chambers, a crank shaft having cranks 15 distributed at 120° around the crank circle, liners in said explosion chambers having exhaust ports therein, differential pistons in said cylinders, packing rings in said liners to prevent leakage from pumping to explosion chambers, means for admitting gas 20 to the pumping chambers of the cylinders and means for admitting gas from the pumping chamber of one cylinder to the explosion chamber of another cylinder.
3. In an internal combustion engine, of the type referred to, the combination of three cylinders having explosion and pumping chambers, a crank shaft having cranks 25 distributed at 120° around the crank circle, 30 liners in said explosion chambers having exhaust ports therein, differential pistons in said cylinders, packing rings in said liners to prevent leakage from pumping to explosion chambers, means for admitting gas 35 to the pumping chambers of the cylinders and means for admitting gas from the pumping chamber of one cylinder to the 40 explosion chamber of another cylinder.

In testimony whereof I affix my signature in presence of two witnesses.

CECIL WEBB.
